UNITED STATES PATENT OFFICE.

CHARLES BALLREICH, OF PUEBLO, COLORADO.

HAND RAZOR-STROPPER.

No. 909,050.

Specification of Letters Patent.

Patented Jan. 5, 1909.

Application filed June 8, 1906. Serial No. 320,808.

To all whom it may concern:

Be it known that I, CHARLES BALLREICH, a citizen of the United States, residing at Pueblo, in the county of Pueblo and State of Colorado, have invented certain new and useful Improvements in Hand Razor-Stroppers, of which the following is a specification.

My invention relates to a device for sharpening razor blades, and consists of a device in which a rotatable cylinder is supported in juxtaposition to a rocking support for a razor blade, and means whereby the latter may be presented tangentially to the cylinder and held under stress, and in certain details of construction fully set forth herein-after and illustrated in the accompanying drawing, in which,—

Figure 1 is a perspective illustration of my improved device; Fig. 2 is a side elevation in part section; Fig. 3, a transverse sectional elevation; and Fig. 4, a sectional elevation showing a modification.

A frame A of any suitable construction, provided with a handle or holder B, supports the operating parts. These parts essentially consist of a cylinder C, a support D for the razor blade, and means for rotating the cylinder and rocking the support, and holding the latter so that the blade X is held under stress against the surface of the cylinder in a position about tangential to the latter. As shown, the cylinder is mounted upon a shaft 1 which extends through the frame, and is provided with a handle 20, and the rotation of this shaft is the means of rocking the support D. Preferably, the support is rocked first in one direction and then in the other, so as to present the blade to the cylinder, first at one side and then at the other, the cylinder being rotated any desired number of times before reversing the position of the blade, and the rotation of the shaft is made the means also, in connection with other devices, of holding the blade under stress so as to bear with considerable force against the face of the cylinder.

As shown, the support D has trunnions 2 to one of which is secured a grooved pulley 3, and a friction band 4 of any suitable character passes around said pulley and around the pulley 5 on the shaft 1. As a result, upon turning the shaft 1, the support D is rocked until the blade is brought to bear upon the face of the cylinder, after which the band 4 will be carried by the pulley 5, but will slip around the pulley 3 in contact therewith,

exerting a friction action, tending to turn the pulley and holding the blade under stress against the cylinder. When the motion of the handle is reversed, the cylinder is turned in the opposite direction and the position of the support D is reversed, and to prevent any possible cutting of the cylinder when latter is used as a buffer, I provide means whereby the reversal of the support takes place before the cylinder begins to rotate. As shown, this is secured by providing the shaft 1 with a lug 6 arranged between two separated shoulders 7, 8, of the cylinder so that the shaft 1 can turn to a limited extent 60 in either direction before the lug is carried from one shoulder to the other.

The cylinder may be a buffing cylinder provided with a soft leather facing 9, or it may be a grinding cylinder of any suitable character so as to act as a hone.

To prevent the cylinder from turning freely on the shaft in changing the direction of rotation, I provide it with a spring 14 bearing upon a washer 15, which is carried 70 with the cylinder and bears upon the side of the frame.

The support D is provided with any suitable clamping means and is formed according to the character of the blade to be clamped. As shown, it is adapted to support the blade of a Gillette razor, and has two lugs 10, 10 adapted to the recesses of said blade, and a hinged clamping plate 12 which may be brought down against the 80 blade and then secured by a sliding bolt 13.

In Fig. 4 I have shown the device as provided with two cylinders for sharpening both edges of a double-edged blade, or for simultaneously sharpening two blades. In this case there is added a second cylinder C', and the shaft 1 carries two pulleys, one at each end, the band 4 of one pulley passing to a pulley on the trunnion of the support, while the band 17 from the other pulley passes to 90 a pulley 18, shown in dotted lines, on the shaft 19 of the cylinder C'.

Without limiting myself to the construction shown, I claim:—

1. The combination with the cylinder and rocking blade support and means for rocking the support and holding it under stress with the blade against the cylinder, of a shaft, and means whereby the cylinder is turned from the shaft in each direction after 100 the rocking of the support.

2. The combination with the cylinder and

- rocking blade support and means for rocking the support and holding it under stress with the blade against the cylinder, of a shaft extending through the cylinder and 5 rotatable to a limited extent in each direction independently thereof, and means whereby the cylinder is turned from the shaft in each direction after the rocking of the support.
- 10 3. The combination with the cylinder and means for rotating the same in each direction, a rocking support for a razor blade parallel to the cylinder, and means for turning the cylinder connected frictionally with the 15 support to rock and hold the latter under stress.
4. The combination with the rotatable cylinder, shaft and pulley, of a rocking razor blade support and pulley and driving band 20 passing round both pulleys, all arranged to present the blade to bear tangentially on the cylinder.
- 25 5. The combination with the rotatable cylinder, shaft and pulley, of a rocking razor blade support and pulley and driving band passing round both pulleys, all arranged to 30 present the blade to bear tangentially on the cylinder, and means whereby the shaft is capable of a limited rotation independently of the cylinder.
- 30 6. The combination in a razor-blade sharpener, of a cylinder rotatable in both directions, a rocking support for a blade parallel to said cylinder and adapted to be turned to

present either side of the blade, at the edge, 35 to the cylinder, and means for rotating the cylinder and rocking the support to hold the blade under stress in constant contact with said cylinder during the continuous rotation of the cylinder in either direction. 40

7. In a device of the class described, a rotatable sharpening member, means to rotate it first in one and then in the other direction, a holder for the blade to be sharpened, and means to automatically reverse the blade-holder at each reversal of rotation of the sharpening member and apply the blade properly thereto to be acted upon and sharpened. 45

8. In a device of the class described, a rotatable sharpening member, means to rotate it first in one and then in the other direction, and to stop rotation for a predetermined period at each reversal of direction, a holder for the blade to be sharpened, and means to 50 automatically reverse the blade-holder at each reversal of rotation of the sharpening member during the period the latter is non-rotating, whereby the blade is brought into 55 operative engagement with the sharpening member before the rotation of the latter is begun. 60

In testimony whereof I affix my signature in presence of two witnesses.

CHARLES BALLREICH.
